LADY'S HANDBAG

Bernard Stember, East Orange, N. J., assignor to
 Amity Leather Products Co., West Bend, Wis.,
 a corporation of Wisconsin

Application May 10, 1939, Serial No. 272,747

2 Claims. (Cl. 150—33)

This invention relates to improvements in ladies' hand-bags, and more particularly to hand-bags of the type having inner and outer side walls forming therebetween auxiliary outer compartments or side pockets.

The object of the invention is to provide a hand-bag of the type described in which the mouth or opening of the side pockets will be held in closed position when the bag is carried.

The foregoing object is accomplished by securing the straps comprising the handle of the bag to the frame and passing them through cut-outs in the top edge of the outer side walls. The straps pull the outer side walls toward the inner side walls and frame, closing the opening or mouth of the side pocket.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Figure 1 is a view in front elevation of a lady's hand-bag embodying the invention;

Figure 2 is a top view of the hand-bag with the mouth of the side pocket in closed position;

Figure 3 is a top view of the hand-bag with the mouth of the side pockets open;

Figure 4 is a transverse sectional view of the hand-bag, taken on line 4—4 of Figure 2;

Figure 5 is a transverse sectional view of the hand-bag, taken on line 5—5 of Figure 3; and

Figure 6 is a transverse sectional view of a hand-bag embodying a modification of the invention.

Referring in greater detail to the drawing, the bag generally comprises outer side walls 10, which form the outline of the hand-bag, as is illustrated in Figure 1. The lower edges of the outer side walls 10 are secured to a bottom (not shown) extending therebetween. The side edges of the outer walls 10, with the exception of a short portion at the top thereof, and the ends of the bottom are joined together by end walls 12. Positioned within the confines of the outer walls is a bag frame 13 which is formed in the manner generally known in the art and comprises two hinged members.

The top of the frame 13 is positioned below the top edges of the outer side walls. With the exception of portions indicated at 14, which are

left free to permit the legs of the frame 13 to be positioned inwardly of the side edges of the outer walls 10, the top edges of the end walls 12 are secured to the depending legs of the frame in a well-known manner. Secured to the top and legs of the bag frame 13 are the edges of the inner walls 15 which generally comprise the main or inner pocket.

The frame 13 is held in closed position by a clasp 16 of the type generally known in the art, and provides the access to the main or inner pocket. It is to be understood that the outer walls, bottom, and end walls may be formed of leather, or other material suitable for use of the article as a hand-bag. Likewise, the inner walls 15 are formed of leather or other material of similar characteristics. The inner surface of the outer walls 10 and the outer surface of the inner walls 15 can be provided with a lining material of silk, or the like, which forms the receiving surface of the auxiliary or side pockets. It may be also advisable to provide stiffening or backing material for the unexposed surfaces of the various walls.

Constructed as heretofore described, it will be noted that the top edge of the outer walls 10 is not secured to the frame, and may be drawn away therefrom, as is clearly illustrated in Figures 3 and 5, to permit easy access to the auxiliary or side pockets designated at S. It is essential, however, to prevent the top edges of the side walls 10 from falling away from the frame 13 when the hand-bag is being carried. To prevent this, there is provided on the frame laterally extending staple head studs 17. Opposite these staple head studs the outer side walls 10 are provided with openings or cut-outs 18 which are adapted to receive the laterally extending staple head studs 17 when the side walls are moved to position immediately adjacent the frame 13. When in this position, the head of the stud extends beyond the outer surface of the side walls 10. A two-part handle is used comprising two straps 19a and 19b, the ends of strap 19a being secured to the staples laterally extending from one side of the frame, and the ends of straps 19b being secured to the staples extending from the other side of the frame.

The bag is normally carried by grasping both straps forming the handle. In this position the sides 10 will be forced toward and in close relation with the top of the frame. The heads of the studs 17 will project through the cut-outs 18, as is illustrated in Figures 1, 2, and 4. To

obtain ready access to the auxiliary compartments or side pockets S it is only necessary to move the straps 19a and 19b to a position extending laterally from the sides of the bag. The sides 10 may then be moved laterally away from the frame 13 to increase the opening of and permit ready access to the auxiliary compartments or side pockets S. During this lateral movement the cut-outs 18 are slid off from the studs 17 and on to the straps 19a or 19b, as the case may be. The upper edge of the sides 10 may be slid along the straps 19a and 19b an amount sufficient to permit convenient entrance to the side pockets S, as is readily seen from an inspection of Figures 3 and 5. If in this lateral position the handles are grasped by the user to carry the hand-bag, they force the sides 10 back to the closed position heretofore described and illustrated in Figures 1, 2, and 4.

The same results may be accomplished by the modification of the invention shown in Figure 6. In this modification the straps 33a and 33b of the handle are secured to the inner surface of the outer side walls 30 and pass under staple head studs 32 secured to the frame 31. The staple head studs 32 are of similar construction to those heretofore described with the exception that they project only far enough away from the frame 32 to permit the straps 33a and 33b to readily slide thereunder and to permit the sides 30 to come as close to the frame 31 as possible. In this modification, cut-outs in the outer side walls are omitted. Only one end of the hand-bag is shown, but the other end is of similar construction. In other respects the hand-bag is constructed in the same manner as the hand-bag heretofore described and illustrated in Figures 1 to 5, inclusive.

Although there is shown and described certain specific embodiments of the invention, many modifications thereof are possible. The invention is not to be restricted except in so far as is necessitated by the prior art and by the spirit of the appended claims.

I claim:

1. In a handbag, a pair of side wall members

defining in part an inner pocket having an upwardly opening mouth, a pair of closure frame members mounted in the mouth of said pocket and clasp means for maintaining the frame members releasably closed, an outer side wall member externally overlying each side wall member of the inner pocket, means cooperating with the inner and outer side wall members for defining an outer pocket on either side of said inner pocket, said outer pockets each having an upwardly opening mouth in general parallelism with the mouth of said inner pocket, handle means for carrying the bag and for maintaining said outer pockets closed comprising a pair of flexible loop members, each loop member extending slidably through guide means provided on one side wall of the respective outer pockets and having its ends secured to the other side wall member of the respective outer pockets whereby the mouth of the inner pocket is free of said loops at all times and may be opened independently of said outer pockets.

2. In a handbag, a pair of side wall members defining in part an inner pocket having an upwardly opening mouth, a pair of closure frame members mounted in the mouth of said pocket and clasp means for maintaining the frame members releasably closed, an outer side wall member externally overlying each side wall member of the inner pocket, means cooperating with the inner and outer side wall members for defining an outer pocket on either side of said inner pocket, said outer pockets each having an upwardly opening mouth in general parallelism with the mouth of said inner pocket, handle means for carrying the bag and for maintaining said outer pockets closed comprising a pair of flexible loop members, each loop member extending slidably through guide means provided on the outer wall of the respective outer pockets and having its ends secured to the inner side wall of the respective outer pockets whereby the mouth of the inner pocket is free of said loops at all times and may be opened independently of said outer pockets.

BERNARD STEMBER.
